GAS BURNER WITH MODULATED FLAME ORIFICE

Paul F. Swenson, Cleveland Heights, and Milton F. Pravda, Bedford, Ohio, assignors to The Cleveland Research Corporation, Cleveland, Ohio

Application April 7, 1947, Serial No. 739,738

7 Claims. (Cl. 158—117)

1

This invention relates to gas burners and more specifically to gas burners of the so called "modulating type" in which the gas discharge is increased and decreased gradually in response to the heat requirements of a room or space being heated, as distinguished from a burner of the "on" and "off" type in which the gas discharge is intermittently turned on and off in response to the heat requirements.

Attempts have been made heretofore to provide a modulating gas burner but, so far as these applicants are aware, none of the attempts have proven practical or satisfactory. One disadvantage in the modulating burner heretofore provided has been that when the burner had numerous discharge openings for the gas and air mixture and the gas supply to the burner was throttled down to a condition corresponding with a low heat requirement, the flame could not be sustained at all of the discharge openings. This resulted in the issuance of unburned gas from certain of the openings and the unburned gas passing up the flue was not only uneconomical but created a dangerous condition. Moreover, the burning of the mixture from only a portion of the burner openings also created a condition in which a complete extinguishment of the flame could easily be produced by the occurrence of a down-draft.

To eliminate the undesirable condition just described attempts have been made to construct a modulating gas burner with fewer burner openings and to make the burner openings of larger size. Another disadvantage was then encountered in that when the gas discharge in the burner was throttled down to a condition corresponding with a low heat requirement, backfires in the burner were a frequent occurrence. The backfires caused the gas to burn at the discharge orifice instead of at the burner openings and this also created an unsatisfactory and hazardous condition.

The present invention provides an improved modulating gas burner of a simple and inexpensive construction capable of functioning in a safe and economical manner and in which the above and other disadvantages are overcome.

Another object of this invention is to provide a modulating gas burner in which the gas stream and the gas and air mixture stream are varied simultaneously so that an efficient and dependable functioning will be obtained throughout substantially the entire range of burner operation.

A further object of the invention is to provide a modulating gas burner in which the size of the

2

gas delivery orifice and the size of the gas and air mixture discharge opening are varied simultaneously by gradually increasing or decreasing the same.

5 Still another object is to provide a gas burner of the character mentioned, in which the gas delivery orifice, the gas and air mixture discharge opening and the combustion air passage are varied simultaneously by gradually increasing or decreasing the same.

10 Yet another object is to provide a gas burner of this character, in which gas pressure responsive means is employed for varying the gas stream, the mixture stream and the supply of combustion air.

15 A further object is to provide a gas burner of this character, in which temperature responsive means is employed for controlling the variation being produced in the gas stream, the mixture stream and the combustion air stream, by the gas pressure responsive means.

20 As another of its objects this invention provides an improved gas burner of the character mentioned, in which the volume of the gas stream and the volume of the gas and air mixture stream can be simultaneously varied gradually and throughout substantially the entire range of burner operation in response to heat requirements but in which a desired discharge velocity 25 is maintained for these streams such that a safe and efficient functioning of the burner will be obtained at all times.

30 The invention can be further briefly summarized as consisting in certain novel combinations and arrangements of parts, hereinafter described and particularly set out in the appended claims.

In the accompanying sheets of drawings,

Fig. 1 is an elevational view, mainly in vertical section, showing a modulating gas burner embodying the present invention, the view also including control devices associated with the burner and which are likewise shown in section.

Fig. 2 is a partial vertical sectional view taken through the upper portion of the pilot burner and showing this portion on a larger scale.

Fig. 3 is a partial vertical sectional view taken through the lower portion of the pilot burner and showing this portion on a larger scale, and

Fig. 4 is an elevational view, mainly in vertical section, showing another modulating gas burner embodying the present invention.

As one practical embodiment of the invention Fig. 1 shows a modulating gas burner 10 which comprises, in general, a hollow casing 11 and a pair of coaxial outer and inner burner tubes 12

and 13. In this instance the burner 10 is shown in an upright position in which the casing 11 forms the base of the unit and the burner tubes 12 and 13 extend substantially vertically above the casing. It will be understood of course that a modulating gas burner embodying the same characteristics and features as the burner 10 can be designed for operation in a horizontal position or in any other desired position or location. The burner 10 is also shown in this instance as being installed in a domestic furnace or the like F which is here represented by the side wall portion 14 and the refractory slab 15. It should be understood, however, that the burner 10 is applicable to all kinds of heating service and can be used for any desired purpose.

The outer burner tube 12 is supported by the casing 11 and has its outwardly flared lower end 12a connected therewith as by means of the screws 16. The lower end of this outer burner tube is spaced from the casing 11 so as to provide therebetween an annular air inlet opening 17. The burner tube can be maintained in this relation to the casing 11 by suitable spacers 18 through which the screws 16 extend. The upper end of the burner tube 12 extends into an opening 15a of the refractory slab 15 and carries a deflector plate 19. The deflector plate extends transversely of the open upper end of the burner tube 12 and is mounted thereon as by a plurality of circumferentially spaced axial arms 21. A second refractory slab 22 is supported by the deflector plate 19 and held thereby in spaced relation above the refractory slab 15. The slab 22 has a central opening 22a therein and can be maintained in position on the deflector plate 19 by means of a stem 19a provided on the latter and which engages in this central opening.

The casing 11 has a gas supply connection 24 connected therewith in the form of a pipe which extends to a suitable source of gas under pressure. The casing also has a gas delivery nozzle 25 mounted on the upper side thereof and located substantially on the common axis of the burner tubes 12 and 13. The nozzle 25 is supplied with gas from the connection 24 through the casing 11, as will be explained in detail hereinafter, and has an outwardly converging orifice or passage 26 for discharging a stream of gas axially of the burner tubes.

The inner burner tube 13, which is at times referred to as a mixing tube, extends longitudinally in the outer burner tube 12 and is spaced therefrom so as to provide therebetween an annular passage 27 for secondary combustion air. The tube 13 has approximately the shape of a Venturi tube and is disposed with its outwardly flared lower end 13a located immediately above the nozzle 25 so that the discharge of a velocity stream of gas from the nozzle will induce a flow of primary combustion air into such lower end for mixing with the gas. The upper end of the tube 13 has an outwardly flared portion 13b which is disposed in adjacently spaced relation to the deflector plate 19 so as to provide therebetween an annular space or discharge opening 29 for the gas and air mixture and from which the gas and air mixture issues as a velocity stream and burns as a sustained flame. The flame produced by this velocity mixture stream travels away from the discharge opening 29 in laterally spreading relation adjacent the underside of the refractory slab 22.

The volume of the gas stream being delivered by the nozzle 25 is varied in accordance with the

heat requirements of the room or space being heated by the burner 10. This variation of the gas stream is accomplished by gradually varying the effective size of the orifice opening 26 by means of a movable valve element 31 which cooperates with the nozzle 25 in forming a metering valve for the gas. The valve element 31 is preferably in the form of the needle valve element here shown and which has an outwardly converging portion 31a which is movable in and cooperates with the tapered nozzle 25 for varying the effective size of the orifice opening 26.

The volume of the gas and air mixture stream is varied simultaneously with, and in corresponding relation to, the variation in the volume of the gas stream being delivered from the nozzle 25. For this purpose the mixing tube 13 is movable axially of the burner unit so as to vary the spacing of its flared upper end 13b relative to the deflector plate 19. The mixing tube 13 is adapted to be shifted by the movement which is imparted to the valve element 31 for varying the gas stream and, to this end, the valve element has an upwardly extending stem extension 31b on which the mixing tube 13 is mounted as by means of the spider 32.

With the construction and arrangement just described it will be seen that when the valve element 31 is moved upwardly, that is, in a direction outwardly of the nozzle 25 to decrease the volume of the stream of gas being delivered from the nozzle, the mixing tube 13 will also be moved upwardly causing its flared end 13b to approach the deflector plate 19 and thereby decrease the size of the gas and air mixture discharge opening 29. Conversely, when the valve element 31 is moved in the opposite direction, that is, inwardly of the nozzle 25 to increase the size of the orifice opening 26 and the volume of the gas stream being discharged therefrom, the flared upper end 13b of the mixing tube 13 will be shifted away from the deflector plate 19 thereby increasing the size of the mixture discharge opening 29. During these axial movements of the mixing tube 13 its flared upper end will be guided by the group of axially extending arms 21.

For the efficient functioning of the modulating burner 10 it is desirable to control the supply of combustion air simultaneously with the control of the gas stream and the gas and air mixture stream. In the gas burner illustrated in Fig. 1 this is accomplished by the damper 34 which is connected with the lower end of the mixing tube 13 for movement therewith and controls the flow of combustion air into the burner through the air inlet opening 17. The damper 34 is here shown as comprising a dished sheet metal disc having a central opening 34a surrounding the nozzle 25 and guided thereon. The damper can be connected with the mixing tube 13 as by means of a plurality of spaced rods 35 so as to leave an opening or passage 36 between the damper and the lower end of the mixing tube for the above mentioned flow of primary combustion air into such lower end of the mixing tube.

When the valve element 31 and the mixing tube 13 are moved in an upward direction to decrease the volumes of the gas stream and the mixture stream as explained above, the damper 34 approaches the flared lower end 12a of the outer burner tube to decrease the effective size of the air inlet opening 17. This causes the volume of both primary and secondary combustion air to be decreased. Conversely, when the valve element 31 and the mixing tube 13 are moved down-

wardly to increase the volumes of the gas stream and mixture stream as explained above, the damper 34 is shifted away from the flared end 12a of the outer tube thereby increasing the effective size of the air inlet opening 17 and permitting increased volumes of primary and secondary combustion air to flow upwardly into the mixing tube 13 and the annular passage 27, respectively.

Although movement can be imparted to the valve element 31, the mixing tube 13 and the damper 34 in any suitable manner and by any appropriate means for the accomplishment of the above described stream volume variation, the embodiment of the invention illustrated in Fig. 1 utilizes the pressure of the gas for this purpose. Attention is now directed to the casing 11 in which gas pressure responsive means suitable for this purpose is housed. The casing 11 comprises top and bottom sections 11a and 11b and two intermediate ring-shaped sections 11c and 11d. These casing sections are suitably connected together with a flexible pressure regulating diaphragm 37 disposed between the casing sections 11b and 11d, and a flexible control diaphragm 38 disposed between the casing sections 11a and 11c. A substantially rigid partition plate or wall 39 is disposed between the casing sections 11c and 11d.

In the casing 11 as just described above the diaphragm 37 cooperates with the bottom casing section 11b to define a gas inlet compartment 40 with which the supply connection 24 communicates through a valve passage 41. The diaphragm 37 cooperates with the partition plate 39 to define therebetween a breather space or compartment 42 which is connected with the atmosphere by a conduit 43 having its outlet end 43a located in or adjacent the lower end of the mixing tube 13. The diaphragm 38 cooperates with the partition plate 39 to define therebetween a control compartment 44 and also cooperates with the top casing section 11a to define therebetween a supply compartment 45.

The inlet compartment 40 and the supply compartment 45 are in constant communication with each other through a passage 46 formed in the wall of the casing 11. The passage of the gas delivery nozzle 25 is also constantly in communication with the supply compartment 45 through the openings 47 of the sleeve or spider 48 in which the needle valve element 31 is guided. The control compartment 44 is connected with the supply compartment 45 through a restricted pressure equalizing passage 49 which can be varied in size by adjustment of the screw 50. The adjusting screw 50 is mounted in the wall of the casing 11 and access thereto can be had by removing the cover screw 51. The control compartment 44 has a restricted bleed outlet 52 leading therefrom and which can be varied in size by means of the adjusting screw 53. A bleed conduit 54 connected with the restricted outlet 52 leads to a pilot burner unit 55 which will be described hereinafter.

The pressure of the gas which is supplied to the nozzle 25 through the casing 11 is preferably regulated so that it will be maintained substantially constant. For this purpose a pressure regulating valve is provided in the casing 11 and controls the valve passage 41. This pressure regulating valve is formed in part by the pressure regulating diaphragm 37 and in part by a valve element 57 which is connected with the diaphragm by means of the screw 58. The valve element 57 cooperates with a seat surrounding the valve

passage 41 and, in this instance, the valve seat is formed by the packing ring 59. The pressure regulating valve also includes a tension spring 60 having one end thereof connected with the valve element 57 and the other end connected with a spring seat 61. The valve element 57 and the tension spring 60 are disposed in a valve chamber 62 and the spring seat 61 is connected with the screw cover 63 of this valve chamber by means of the adjusting screw 64. The screw 64 is threaded into the spring seat 61 so that the tension of the spring 60 can be adjusted by rotating this screw. Access to the adjusting screw 64 can be had by removing the screw plug 65 of the cover 63.

The valve element 57 of the pressure regulating valve is normally held in its open position, as shown in Fig. 1, by the tension spring 60 so that gas from the supply connection 24 can flow readily into the inlet chamber 40 through the valve passage 41 and thence through the connecting passage 46 and through the supply compartment 45 to the gas delivery nozzle 25. When the pressure of the gas in the inlet compartment 40 increases, it acts against the underside of the diaphragm 37 and lifts the diaphragm against the tension of the spring 60 thereby moving the valve element 57 toward the seat 59 and decreasing the size of the valve passage 41 and thereby restricting the flow of gas into the inlet compartment 40. As the gas pressure in the inlet compartment 40 decreases, the diaphragm 37 and the valve element 57 are moved downwardly by the tension spring 60 thereby increasing the size of the valve passage 41 and facilitating the flow of gas into the inlet compartment. These fluctuations of the diaphragm 37 and the corresponding movements of the valve element 57 result in the pressure of the gas in the inlet compartment 40 and in the supply compartment 45 being maintained substantially constant regardless of pressure variations occurring in the supply connection 24 and regardless of variations occurring in the volume of the gas stream being delivered from the nozzle 25 as a result of movements of the needle valve element 31.

The portion of the casing 11 which contains the valve chamber 62 has spaced projections 66 thereon forming stops adapted to be engaged by the diaphragm 37 during downward movement of the latter. These stops maintain the diaphragm in spaced relation to the valve passage 41 when the diaphragm moves to its lowermost position.

As shown in Fig. 1, the lower end of the needle valve element 31 is connected with the control diaphragm 38 by means of the screw 68 so that movements of this diaphragm in response to a pressure differential between the control compartment 44 and the supply compartment 45 will cause actuation of this valve element. A compression spring 69 is disposed in the control compartment 44 and has opposite ends thereof in engagement, respectively, with the rigid partition plate 39 and the flexible diaphragm 38. This spring is preferably a tapered or conical spring of low rate characteristic which assists the diaphragm 38 in moving the valve element 31 in a direction to decrease the size of the orifice opening 26. The characteristics of the spring 69 are such that this spring carries and substantially balances the load represented by the weight of the needle valve element 31, the mixing tube 13 and the damper 34.

When the escape or bleeding of gas from the

control compartment 44 through the restricted outlet 52 is prevented and the gas pressure on opposite sides of the diaphragm 38 has equalized through the restricted passage 49, the spring 69 will shift the valve element 31 upwardly and hold this valve element in its closed position. When gas is bled or permitted to escape from control compartment 44 through the restricted passage 52, the pressure in the control compartment drops and is overbalanced by the gas pressure in the supply compartment 45 causing downward movement of the diaphragm 38 and a corresponding downward or opening movement of the valve element 31. Increase or decrease in the flow of gas out of the control compartment 44 through the restricted passage 52 results in a corresponding downward opening or upward closing movement of the valve element 31. It will accordingly be seen that by controlling the pressure of the gas in the control compartment 44, the gas pressure actuation of the valve element 31 can be controlled in a positive and sensitive manner for modulating the gas flame.

The escape or bleeding of gas from the control compartment 44 for the above explained purpose can be controlled by the use of any appropriate control device or devices. In the modulating gas burner illustrated in Fig. 1 the escape of gas from the control compartment 44 is controlled by the pilot burner unit 55 and also by the two additional control devices 71 and 72. The pilot burner unit 55 and the control devices 71 and 72 are disposed in a series relationship or circuit, that is to say, the gas bled from the control compartment 44 first flows to the pilot burner unit, then to the control device 71 and then to the control device 72.

The control device 71 may be a temperature responsive limit control device which is associated with the heating furnace F being served by the burner unit 10 and hence is disposed in local relation to the burner unit. The control device 72 may be a room thermostat which is located relatively remote from the burner 10 such as in a room or other space to which heat is supplied by the burner. The control gas circuit in which the pilot burner unit 55 and the control devices 71 and 72 are located includes the bleed conduit 54 which connects the pilot burner unit with the restricted outlet 52 of the control compartment 44, a conduit 73 which connects the control device 71 with the pilot burner unit and a conduit 74 which connects the control device 72 with the control device 71. This control circuit also includes a return conduit 75 which connects the control device 72 with the gas escape conduit 43.

The pilot burner unit 55 is itself of novel construction and cooperates with the main burner in a novel manner. This pilot burner unit is provided with a burner tube 77 which is mounted on the main burner tube 12 as by means of the bracket 78 and includes a head 79 which is mounted on the upper end of the burner tube 77. The pilot burner unit also includes an auxiliary burner tube 80 which projects from the upper end of the burner tube 77 and extends through the head 79. The pilot burner unit 55 is disposed in the secondary combustion air passage 27 of the main burner and is located therein so that the upper end of the auxiliary burner tube 80 will occupy a position near the discharge opening 29 of the main burner.

The auxiliary burner tube 80 is open at its upper end and may also have side openings 81 therein adjacent its upper end. A gas and air

mixture is discharged continuously from the end and side openings of the auxiliary burner tube 80 for maintaining a pilot flame P1 adjacent the discharge opening 29 of the main burner. The burner tube 77 is provided with one or more air inlet openings 82 and with a gas delivery nozzle 83. The lower end of the auxiliary burner tube 80 has openings 84 therein by which it is connected with the interior of the burner tube 77 to receive a gas and air mixture from the latter. The discharge of gas from the nozzle 83 induces a flow of air into the burner tube 77 through the openings 82 for mixing with such gas. A supply of gas is fed continuously to the pilot burner unit 55 through a conduit 85 which connects the gas delivery nozzle 83 with the inlet compartment 40 of the casing 11 through a manually adjustable control valve 86. The conduit 85 is connected with the passage of the nozzle 83 through the groove 87 and the inclined passages 88 formed in the plug portion 83a of the nozzle.

The head 79 which is carried by the pilot burner tube 77 also has a discharge opening 89 for discharging gas and air mixture from the tube 77 and which opening surrounds the auxiliary burner tube 80. The head 79 also has a recess 90 therein connecting the discharge opening 89 with a flame space 91 which is defined in part by a bracket portion 79a of the head and in part by a bimetal temperature responsive arm 92 which overlies the flame space. The gas and air mixture which issues from the discharge opening 89 and the recess 90 burns as a sustained pilot flame P2 which plays against the underside of the temperature responsive arm 92. The sides of the flame space 91 are open and permit the flame P2 to spread laterally and rise on opposite sides of the temperature responsive arm 92 as shown in Fig. 2.

The delivery of gas through the nozzle 83 of the pilot burner unit 55 is controlled by an axially movable needle valve element 93 having a stem extension 93a on which the auxiliary burner tube 80 is mounted. The discharge opening 89 is controlled by a valve element 94 which is here shown in the form of a collar carried by the axially movable auxiliary burner tube 80. Downward or opening movement is imparted to the valve element 93 through the auxiliary burner tube 80 by the temperature responsive arm 92 which has one end thereof anchored on the bracket portion 79a of the head 79 by means of the screw 95. The arm 92 extends laterally in overlying relation to the space 91 and the free end of this arm is in the form of a fork 96 which straddles the auxiliary burner tube 80 immediately above a transverse pin 97 carried by the latter.

In this position the temperature responsive arm 92 will be contacted by the pilot flame P2 formed by the burning of the gas and air mixture issuing from the opening 89 and will act to automatically maintain the flame P2 at a desired predetermined size or temperature value. Whenever the arm 92 cools it will be deflected downwardly causing the auxiliary burner tube 80 and the valve element 93 to be shifted in a downward direction by the pressure of the forked end 96 on the pin 97. This downward movement increases the opening of the gas delivery nozzle 83 thereby increasing the supply of gas for the pilot flame P2. Conversely, whenever the temperature of the arm 92 increases above a predetermined value this arm will be deflected upwardly thereby releasing the pin 97 and permitting the valve element 93 and the auxiliary burner tube 80 to be lifted by a

compression spring 99 which is embodied in the pilot burner and located beneath the control gas valve 100. This upward movement of the valve element 93 decreases the size of the opening of the delivery nozzle 83 and thereby reduces the supply of the gas for the pilot flame P2.

In this manner the temperature responsive arm 92 automatically controls and varies the supply of gas for the pilot flame P2 and maintains this gas supply at such a volume that an adequate but not excessive heating of the arm 92 will take place. The pilot flame P1 which burns from the upper end of the auxiliary burner tube 80 will burn continuously at approximately the same flame size but the pilot flame P2 will be gradually varied or modulated, as explained above, in accordance with the temperature condition influencing the temperature responsive arm 92. As shown in Figs. 1 and 2 the arm 92 can be protected from the heat of the main burner flame by means of a guard 101 which is disposed over this arm and is held in place by the screw 95.

The lower portion of the pilot burner unit 55 contains the above mentioned control valve member 100 which constitutes one of the series controls for controlling the bleeding of gas from the control compartment 44 of the casing 11. This valve member controls the flow of gas from the conduit 54 into the conduit 73 leading to the control device 71. During such time that the pilot burner 55 is ignited, a relatively hot condition exists for the temperature responsive arm 92 and this arm will then be deflected upwardly, as explained above, and this will permit the spring 99 to lift the valve member 100 to its open position in which gas can be bled from the control compartment 44 and will be permitted to flow into the conduit 73 to the temperature responsive limit control device 71. During the time that the pilot burner 55 is extinguished, the arm 92 will be relatively cool and will be deflected downwardly to a position in which the control valve member 100 will be held closed by the lower end of the valve element 93 and even though the temperature responsive devices 71 and 72 should call for operation of the main burner, the signal will not be transmitted to the control compartment 44 and the valve element 31 of the main burner will remain closed.

The temperature responsive limit control device 71 may be any suitable form of device of this type and, in this instance, comprises a body 102 adapted to be mounted on the furnace structure 14 and having a valve passage 103 and a valve chamber 104 therein connecting conduit 73 with the conduit 74. A valve member 105 movable in the valve chamber 104 controls the passage 103 and is adapted to be moved toward a closed position in opposition to a compression spring 106 by the bimetal element 107 acting through the stem 108. A flexible member or bellows 109 forms a seal for the passage through which the stem 108 extends and prevents the escape of gas from the valve chamber 104 around this stem. The actuation of the valve member 105 by the bimetal element 107 can be adjusted or calibrated by means of the thumb screw 110 which varies the compression of the spring 106.

The temperature responsive device 72 is a room thermostat or the like comprising a suitable casting 112 containing a body 113 having a valve chamber 114 therein with which the return conduit 75 is connected. A valve passage 115 is controlled by a movable valve member 116 and connects the supply conduit 74 with the valve cham-

ber 114. The valve member 116 is moved toward its closed position by a temperature responsive member 117 which is here shown in the form of an expansible temperature responsive bellows device. The bellows device 117 acts through a lever 118 which is rockable on the pivot 119 and imparts movement to a valve actuating stem 120 in a direction to close the valve member 116 in opposition to the compression spring 106. The action of the bellows 117 can be adjusted or calibrated by means of the adjusting screw 122 which carries a graduated dial 123, the latter being movable relative to a fixed pointer 124.

Whenever the room temperature is relatively low a contraction of the bellows 117 permits the valve member 116 to be opened by the spring 106 and this permits the bleeding of gas from the control compartment 44 of the casing 11, provided that the control valve member 100 of the pilot burner unit 55 and the valve member 105 of the limit control device 71, are open. The escape of gas from the control compartment 44 causes the above explained opening movement of the needle valve element 31 of the main burner 10 which increases the volume of the gas stream being delivered from the nozzle 25. If the pilot burner unit is extinguished the control valve member 100 will be held closed, as explained above, or if the operating temperature of the furnace F is excessive the valve member 105 of the control device 71 will remain closed and, in either event, the opening of the valve member 116 of the room thermostat will not cause bleeding of gas from the control compartment 44 and at this time the pressures in the control compartment 44 and the supply compartment 45 will be equalized and the spring 69 will hold the needle valve element 31 closed. When the pilot burner 55 is lighted and the temperature of the furnace F is not excessive, the control valve members 100 and 105 will be open and a modulating control of the main burner will then be carried out by the room thermostat 72.

Since the return conduit 75 connects with the conduit 43 leading to the mixing tube 27 it will be seen that the small flow of control gas which is bled from the control chamber 44 and which has passed in series relation through the valve chamber of the pilot burner unit 55, the valve chamber of the control device 71 and the valve chamber of the thermostat 72, will be returned to the main burner and will be mixed with the air stream and burned as a part of the main burner flame.

In connection with the construction and operation of the burner 10 it will be observed that if a down-draft occurs it will travel downwardly relatively freely in the annular passage 27 because the latter is in open communication with the main combustion chamber with which the burner is being used. This movement of the down-draft will be arrested by the damper 17 which acts as a barrier thereby causing the velocity flow of the down-draft to be converted into a pressure at this point which moves upwardly into the lower end of the mixing tube 13. Although some of the down-draft stream may attempt to enter the upper end of the mixing tube 13 it will be met and equalized by the upward pressure surge from the lower end and will thus be prevented from blowing out the gas flame.

Fig. 4 of the drawings shows another modulating gas burner 130 which is generally similar to the burner 10 above described but which is of a more simplified construction. The burner 130

11

comprises coaxial outer and inner burner tubes 131 and 132 having an annular secondary combustion air passage 133 therebetween and a hollow control casing 134 through which the gas is supplied to a gas delivery nozzle 135. The outer burner tube 131 is mounted on the casing 134 by the spaced studs 136 so as to provide therebetween an inlet opening or passage 137 for combustion air.

The upper end of the outer burner tube extends into an opening of a refractory slab 138 which may form a portion of the wall of the combustion chamber with which the burner is being used. A second refractory slab 139 is supported from the upper end of the outer burner tube in spaced relation to the slab 138. The slab 139 can be mounted on the outer burner tube 131 by means of the bridge member 140 having spaced axial arms 140a which are connected with the upper end of the outer burner tube.

The inner burner tube 132 may be in the form of Venturi tube as here shown and is mounted in the outer tube 131 by means of a group of radially extending arms 141 which extend through the inner tube and have their outer ends connected to the outer tube. The inner tube is disposed in axial alignment with the nozzle 135 and has its lower end in adjacently spaced relation to this nozzle so that a velocity stream of gas being discharged through the orifice 142 of the nozzle will be directed upwardly through the inner tube and will induce a flow of primary combustion air into the lower end of this tube from the air inlet opening 137. The upper end of the inner tube is disposed so that it lies in substantially the same horizontal plane as the upper end of the outer tube 131. A deflector plate 143, located adjacent the upper end of the inner tube and extending transversely thereof, defines with such upper end of the inner tube a discharge opening or space 145 for discharging a velocity stream of the gas and air mixture being produced in the tube 132. The annular space between the upper ends of the outer and inner tubes 131 and 132 forms a discharge opening 146 for secondary combustion air.

The orifice opening 142 of the gas delivery nozzle 135 is controlled by needle valve element 147 having a tapered portion 148 axially movable in this orifice opening. This needle valve element also has an extension stem portion 149 which extends through, and is guided in a sleeve 150 carried by the inner ends of the arms 141. The deflector plate 143 is mounted on the upper end of the stem extension 149 so that control movements imparted to the needle valve element will also shift the deflector plate for varying the size of the gas discharge opening 145 and the size of the secondary air discharge opening 146.

The direction of the taper 148 of the needle valve element is such that when the latter is moved in a downward direction, that is to say in a direction inwardly of the nozzle 135, the volume of the gas stream being discharged from the nozzle and the size of the orifice opening 142 will be decreased and, conversely upward or outward movement of the tapered portion 148 will increase the size of the orifice opening and the volume of the gas stream being delivered therefrom. The corresponding movements imparted to the deflector plate 143 will be such that when the volume of the gas stream being discharged from the nozzle orifice 142 is decreased the size of the mixture discharge opening 145 and the secondary air discharge opening 146 will likewise be decreased. On the other hand when the move-

12

ment of needle valve element increases the size of the orifice 142 the corresponding movement imparted to the deflector plate 143 will increase the size of the mixture and secondary combustion air discharge openings 145 and 146.

The hollow casing 134 is formed by connected top and bottom casing sections 134a and 134b which have a flexible diaphragm 150 mounted therebetween. This diaphragm divides the interior of the casing 134 into a gas supply compartment 151 and a control compartment 152. A restricted passage 153 formed in the wall of the casing connects the supply and control compartments 151 and 152 and permits a pressure equalization therebetween. The size of the restricted passage 153 can be varied by the adjusting screw 154. The supply compartment 151 is connected with a source of gas under pressure by means of the pipe 155.

The needle valve element 147 which controls the orifice 142 of the gas delivery nozzle 135, is connected with the diaphragm 150 for actuation thereby. This valve element is connected with the diaphragm by means of a tubular stem 157 whose lower end extends through the diaphragm and is in open communication with the supply compartment 151. The upper portion of the tubular stem 157 has openings 158 therein through which the gas from the supply compartment 151 is delivered to the interior of the nozzle 135. The tubular stem portion 157 is axially movable in an opening 159 provided in the base portion 135a of the nozzle 135. The escape of gas through the opening 159 is prevented by a flexible sealing diaphragm 160 having its central portion connected with the central portion of the main flexible diaphragm 150 and whose edge portion 160a is sealingly pressed against the top casing section 134a by the compression spring 161. This compression spring is preferably a tapered low rate spring which also acts on the main diaphragm 150 so as to cooperate with the gas pressure in causing the desired actuation of the needle valve element 147 and the deflector plate 143. A small breather passage 162 is also formed in the base portion 135a of the nozzle 135 and connects the sealing space or chamber 163 surrounding the hollow stem 157 with the interior of the nozzle 135.

The control compartment 152 of the casing 134 has an outlet or bleed conduit 165 connected therewith so that the pressure of the gas in the control compartment can be varied so as to produce a desired pressure differential between the control compartment 152 and the supply compartment 151 for actuating the diaphragm 150 and the needle valve element 147 connected therewith. The escape or bleeding of gas from the control compartment 152 through the conduit 165 can be controlled by suitable control devices, such as the above described limit control device 71 which would be located in local relation to the burner 139 and the room thermostat 72 would be located at a point relatively remote from the burner. When either of these control devices permits the escape of gas from the control compartment 152, the resulting pressure differential on opposite sides of the diaphragm 150 will cause upward movement thereof to thereby lift the needle valve element 147 and increase the orifice opening 142 to correspondingly increase the volume of the gas stream being delivered by the nozzle 135. When either of the control devices 71 and 72 acts to decrease or terminate the escape of gas from the control compartment 152 the resulting equalization of pressure between the

13

control and supply compartments and the action of compression spring 161 cause a downward movement of the diaphragm 150 and a corresponding downward or closing movement of the valve element 147.

In the operation of the burner 130 as just described it will be observed that the movements imparted to the needle valve element 147 and to the deflector plate 143 will be such as to cause a gradual increase or decrease in the size of the gas delivery orifice 142 and in the size of the mixture discharge opening 145 and also in the secondary combustion air discharge opening 146. This gradual variation in the size of these openings produces a desired modulation of the gas flame formed by the combustion of the gas and air mixture being discharged through the opening 145. The gas which is bled from the control compartment 152 can be returned to the burner and discharged into the lower end of the mixing tube 132 by the return conduit 166.

A pilot burner 167 may be provided adjacent the main burner 130 and, in this instance, is of a simple construction comprising merely a gas and air mixing tube 168 extending axially along the outside of the outer burner tube 131 and mounted thereon by means of the brackets 169. The pilot burner 167 also includes a gas delivery nozzle 170 which discharges a stream of gas upwardly through tube 168 but is spaced from the lower end thereof to permit an induced flow of air to enter this tube for mixing with the gas stream. The nozzle 170 is connected with the supply compartment 151 of the casing 134 and the flow of gas through this nozzle can be regulated by means of the adjustable valve key 171. The upper end of the pilot burner 167 extends through the refractory slab 138 and is located opposite the discharge opening 145 so that a pilot flame burning continuously from the upper end of the tube 168 will be in adjacent relation to the discharge opening for igniting the mixture stream issuing therefrom.

In the modulating gas burners 10 and 130 as described above it should be noted that the gas is discharged from the nozzle as a velocity stream which induces a flow of primary combustion air into the mixing tube and the resulting gas and air mixture is discharged from the burner opening as a velocity mixture stream. When the volume of gas being discharged from the nozzle is varied, the size of the mixture discharge opening and the amount of combustion air are varied simultaneously and in corresponding relation. This provides for a gas and air mixture in proper proportions for a substantially complete combustion and a substantially constant flue gas analysis throughout the full range of burner operation, and also insures a velocity discharge of the mixture from the burner opening which at all times prevents the occurrence of a backfire. Even though the volumes of the gas stream and mixture stream are varied the discharge velocity for these streams is maintained and the burners have what can be referred to as a substantially one hundred percent turn down ratio. Because of these characteristics the main burner flame can be gradually increased or decreased in accordance with heat requirements and the burning of the gas will take place safely and efficiently throughout the entire range of burner operation.

In connection with the construction and operation of the burner 130 it will be observed further that the deflector plate 143 shields the upper ends of the burner tubes 131 and 132 and

14

prevents down-drafts from entering these tubes, and hence, the gas flame is not likely to be blown out. The inner tube 132 is particularly well shielded by the deflector 143 and any portion of the down-draft stream which enters the outer tube 131 can pass freely therethrough without materially affecting the gas stream or the flame.

Although the improved gas burner has been disclosed herein to a detailed extent, it should be understood that the invention is not intended to be correspondingly limited in scope but includes all changes and modifications coming within the scope of the appended claims.

Having thus described our invention, we claim:

1. In a gas burner, a housing comprising a casing and a main burner tube connected therewith, a mixing tube member located in said main burner tube and extending substantially coaxially thereof, a deflector member, said mixing tube member having an air inlet at one end thereof and a discharge opening at its other end for discharging a gas and air mixture, said deflector member being located adjacent to and extending transversely of said other end of said mixing tube member and cooperating therewith in defining said discharge opening, one of said members being movable relative to the other axially of said main burner tube for varying said discharge opening, a gas delivery nozzle adapted to discharge a velocity stream of gas in said mixing tube member axially thereof for mixing with air from said air inlet, means for supplying gas under pressure to said nozzle, a movable valve element controlling the delivery of gas from said nozzle, means connecting said one member with said valve element for movement conjointly with the latter, gas pressure responsive diaphragm means in said casing and operable to cause such conjoint movement of said one member and valve element, and pressure regulating valve means in said casing for controlling the pressure of the gas acting on said pressure responsive means.
2. A gas burner of the character described comprising a burner tube having an air inlet, a mixing tube member having one end located to receive air from said inlet, said mixing tube member being disposed in said burner tube and spaced from the wall of the latter to provide therebetween a passage for secondary air from said air inlet, a gas delivery nozzle adapted to discharge gas axially in said mixing tube member for mixing with air from said inlet, a deflector member spaced from the other end of said mixing tube member to provide therebetween a discharge opening for a gas and air mixture, one of said members being shiftable for varying said discharge opening, a movable valve element cooperating with said nozzle for controlling the delivery of gas through the latter, a damper controlling the flow of air through said inlet, said one member and damper being adapted for movement proportionately with said valve element, a hollow casing having supply and control compartments therein and a restricted passage connecting said compartments with each other, a diaphragm in said casing between said compartments and operably connected with said valve element for causing actuation of the valve element, said one member and said damper in response to a pressure differential between said compartments, means for supplying gas under pressure to said nozzle and having communication with said supply compartment, and means

for discharging gas from said control chamber at a controlled rate for creating said pressure differential.

3. A gas burner of the character described comprising, a casing, a burner tube having one end thereof connected with said casing, a mixing tube in said burner tube and spaced from the wall of the latter to provide an air passage therebetween, a deflector mounted on the other end of said burner tube and extending transversely of one end of said mixing tube and spaced therefrom so as to provide therebetween a discharge opening for a gas and air mixture, said mixing tube having an air inlet at its other end and being shiftable relative to said deflector for varying the size of said discharge opening, a gas delivery nozzle adapted to discharge a velocity stream of gas axially of said mixing tube and toward said discharge opening, a movable valve element cooperating with said nozzle for controlling the delivery of gas therefrom and having operative connection with said mixing tube for simultaneously shifting the latter, and gas pressure responsive diaphragm means in said casing and connected with said valve element for causing the simultaneous actuation of said valve element and mixing tube.

4. A gas burner comprising a casing having an inlet for gas under pressure and a gas delivery nozzle connected with said inlet to be supplied therefrom, a burner tube having an air inlet end connected with said casing and provided with an air inlet opening, a deflector carried by said burner tube, a movable valve needle cooperating with said nozzle for controlling the delivery of gas therefrom, a mixing tube in said burner tube and disposed so that gas is discharged thereinto by said nozzle for mixing with air from said air inlet, said mixing tube having one end thereof spaced from said deflector to provide a discharge opening therebetween for a gas and air mixture, means connecting said mixing tube with said valve needle for movement by the latter relative to the deflector for varying said discharge opening, and gas pressure responsive diaphragm means in said casing and adapted to cause simultaneous actuation of said valve needle and mixing tube.

5. A gas burner comprising a casing having an inlet for gas under pressure and a gas delivery nozzle connected with said inlet to be supplied therefrom, a burner tube having an air inlet end connected with said casing and provided with an air inlet opening, a deflector carried by said burner tube, a movable valve needle cooperating with said nozzle for controlling the delivery of gas therefrom, a mixing tube in said burner tube and disposed so that gas is discharged thereinto by said nozzle for mixing with air from said air inlet, said mixing tube having one end thereof spaced from said deflector to provide a discharge opening therebetween for a gas and air mixture, means connecting said mixing tube with said valve needle for movement by the latter relative to the deflector for varying said discharge opening, a movable air control member controlling the flow of air through said air inlet, means connecting said air control member with said valve needle, and gas pressure responsive diaphragm means in said casing and operable to cause actuation of said valve needle, mixing tube and air control member simultaneously.

6. A gas burner comprising a burner tube having an air inlet opening and a discharge opening,

a mixing tube in said burner tube and spaced from the wall thereof to provide a passage therebetween for secondary air, said mixing tube having a discharge opening lying in substantially the same plane as the discharge opening of said burner tube, a gas delivery nozzle adapted to discharge gas into said mixing tube for mixing with air from said air inlet opening, a movable valve needle cooperating with said nozzle for controlling the discharge of gas therefrom, a control member disposed adjacent to and extending transversely of the discharge openings of said burner tube and mixing tube, means connecting said control member with said valve needle for movement thereby relative to said burner tube and said mixing tube for varying said discharge openings, and means for supplying gas under pressure to said nozzle including gas pressure responsive diaphragm means for causing actuation of said valve needle and control member simultaneously.

7. A modulating gas burner comprising a bottom casing having a transverse top wall, an upright burner tube supported by said casing and extending upwardly from said top wall, a mixing tube member extending upwardly within said burner tube in substantially coaxial relation thereto and being spaced from said burner tube to define therebetween an upright annular passage for secondary combustion air, said burner tube being open at its upper end and having an air inlet opening at its lower end adapted to supply said secondary combustion air to said annular passage, said mixing tube member having a substantially Venturi shaped passage and being open at its upper and lower ends and having its lower end disposed above said air inlet opening so as to receive primary combustion air therefrom, a deflector member extending transversely of and spaced from the upper end of said mixing tube member and cooperating therewith in defining an annular discharge opening for a gas and air mixture, said bottom casing having gas supply and control compartments therein and a restricted passage connecting said compartments with each other, a diaphragm in said bottom casing between said compartments and being movable in response to a pressure differential therebetween, a gas delivery nozzle carried by said top wall and disposed so as to discharge a velocity stream of gas from said supply compartment upwardly into the lower end of said mixing tube member for inducing a flow of said primary combustion air thereinto from said air inlet, a valve element axially movable in said nozzle for controlling the discharge of gas therefrom and having its lower end connected with said diaphragm for actuation thereby, one of said members being movable in the direction of the axis of said burner tube and relative to the other of said members for varying the size of said annular discharge opening, means connecting said one member with said valve element to vary said discharge opening proportionately with the opening and closing of the valve element, and means for discharging gas from said control compartment at a controlled rate for creating said pressure differential.
